DESIGN FOR A SHOE SOLE

Joseph B. Reynolds, Hagerstown, Md., assignor to
The Hagerstown Rubber Company, Hagerstown, Md., a corporation of Maryland

Application March 22, 1941, Serial No. 99,778

Term of patent 3½ years

To all whom it may concern:

Be it known that I, Joseph B. Reynolds, a citizen of the United States, residing at Hagerstown, in the county of Washington and State of Maryland, have invented a new, original, and ornamental Design for a Shoe Sole, of which the following is a specification, reference being had to the accompanying drawing, forming part hereof.

I claim:

The ornamental design for a shoe sole, substantially as shown.

JOSEPH B. REYNOLDS.
